Richard S. French, Waterville, Maine, assignor to
Keyes Fibre Company, Portland, Maine, a cor-
poration of Maine

Application June 1, 1951, Serial No. 15,371

Term of patent 14 years

(CL. D58—13)

To all whom it may concern:

Be it known that I, Richard S. French, a citizen of the United States, residing at Waterville, in the county of Kennebec, State of Maine, have invented a new, original, and ornamental Design for Molded Pulp Insulation Member, of which the following is a specification, reference being had to the accompanying drawing, forming part thereof, and wherein:

Fig. 1 is a top plan view of a molded pulp insulation member, showing my new design;

Fig. 2 is a side elevational view thereof; and
Figs. 3 and 4 are cross-sectional views thereof

taken along the lines 3—3 and 4—4 of Fig. 1,
respectively.

I claim:

The ornamental design for a molded pulp in-
sulation member, as shown.

RICHARD S. FRENCH.
